MUSIC SUITE

Tord Kempe, Degeberga, Sweden, assignor to
Abra Mobler AB, Taberg, Sweden

Filed Nov. 6, 1973, Ser. No. 413,264

Claims priority, application Sweden May 7, 1973

Term of patent 14 years

Int. Cl. D6—04

U.S. Cl. D6—159

FIG.3

FIG. 1 is a front and right side perspective view of a music suite showing my new design, the top left sliding door being in opened condition;

FIG. 2 is a front elevational view;

FIG. 3 is a right side elevational view, the left side being a mirror image thereof;

FIG. 4 is a top plan view; and

FIG. 5 is a rear elevational view.

I claim:

The ornamental design for a music suite, substantially as shown and described.
